UNITED STATES PATENT OFFICE.

HERMAN W. FAY AND RICHARD J. SCHUELER, OF ST. LOUIS, MISSOURI.

DESIGN FOR A BOTTLE.

SPECIFICATION forming part of Design No. 23,100, dated March 6, 1894.

Application filed January 26, 1894. Serial No. 498,153. Term of patent 3½ years.

To all whom it may concern:

Be it known that we, HERMAN W. FAY and RICHARD J. SCHUELER, of the city of St. Louis and State of Missouri, have invented and produced a new and original Design for Bottles, of which the following is a specification, reference being had to the accompanying drawings, forming part thereof, in which—

Figure I is a front elevation of a bottle, illustrative of our design. Fig. II is a side elevation of the same. Fig. III is a transverse section taken on line III—III, Fig. I.

The leading features of our design consist in a bottle having one oval and three flat sides, two rounded and two square corners, and a recess which extends across the oval side

of the bottle only, said recess being slightly rounded at the corners.

1 represents the body of the bottle, having flat sides 2, 3, and 4 and rounded rear corners 20 5 and 6, and square front corners 5^a and 6^a.

7 represents the oval side of the bottle, across which extends a recess 8 having rounded corners 9.

We claim as our invention—

The design for a bottle substantially as herein shown and described.

HERMAN W. FAY.

RICHARD J. SCHUELER.

In presence of—

A. M. EBERSOLE,

C. G. EDWARDS.
